UNITED STATES PATENT OFFICE.

OLLIE EARL NICHOLS, OF CRUTCHFIELD, KENTUCKY, ASSIGNOR OF ONE-HALF TO
WILLIAM SIMPSON SEAT, OF CRUTCHFIELD, KENTUCKY.

NICOTINE FILTER FOR TOBACCO PIPES.

Application filed April 18, 1922. Serial No. 555,491.

To all whom it may concern:

Be it known that I, OLLIE EARL NICHOLS, a citizen of the United States, residing at Crutchfield, in the county of Fulton and 5 State of Kentucky, have invented certain new and useful Improvements in a Nicotine Filter for Tobacco Pipes, of which the following is a specification.

This invention relates to tobacco applications.

The primary object of this invention is the provision of an improved tobacco pipe, whereby the draft through the pipe travels a tortuous path, in order to filter nicotine 15 from smoke passing therethrough, without in any way constricting the free flow of the draft.

An important object of this invention is the provision of an improved nicotine filtering member, relatively simple in character, adapted for attachment in the passageways of pipes, whereby the draft through the pipe is over a tortuous path, so that nicotine 20 may be readily and conveniently filtered 25 from smoke passing therethrough.

A further object of this invention is the provision of an improved tobacco pipe of the above described character which is extremely practical in nature and embodies an 30 improved arrangement, enabling the cleansing of the pipe, and means preventing the entrance of nicotine into the mouth of the user, during smoking of the same.

Other objects and advantages of this invention will be apparent during the course 35 of the following detailed description.

In the accompanying drawing, forming a part of this specification, and wherein similar reference characters designate corresponding parts throughout the several views,

Figure 1 is a longitudinal cross sectional view, taken through the improved pipe, showing the nicotine filter arrangement as used in connection therewith.

Figure 2 is an enlarged plan view of a novel type of nicotine filtering member as used in connection with the improved pipe.

Figure 3 is an enlarged longitudinal cross sectional view, taken through the filtering member as illustrated in Figure 2.

Figure 4 is a transverse cross sectional view, taken on the line 4-4 of Figure 3.

Figure 5 is a transverse cross sectional view, taken on the line 5-5 of Figure 3.

Figure 6 is a transverse cross sectional view, taken on the line 6-6 of Figure 3.

In the drawing, wherein for the purpose of illustration is shown but the preferred embodiment of this invention, the letter A designates the improved pipe, which embodies the pipe body or casing B; nicotine filter member C, and mouth inserting end D.

Referring to the pipe casing B, the same may be of any general formation including the tobacco bowl 10, and the stem 11 which is provided with a horizontal passageway 12 longitudinally therethrough as is the ordinary formation.

Referring to the construction of the nicotine filtering member C, the same is preferably of wood, hard rubber or analogous material and is provided with the cylindrical shaped forward and rear ends 15 and 16 respectively. The forward end 15 is preferably provided with a metallic cap 17 upon its extreme inner or forward end, counter sunk thereon, and which construction is provided in order to protect the end 15 of the member C against heat and fire

incident to smoking of the tobacco within the bowl 10, as will be understood when explaining the operation of the improved pipe A. The end 15, as well as the cap 17, is provided with a groove 20, which extends longitudinally along the outer surfaces of said end and said cap and provides a passageway for the draft of the pipe

A, as will be presently described. The rear end 16, which as before mentioned is of cylindrical formation extends beyond the end of the pipe stem and has an enlarged outer end portion 26 so that it may be readily grasped when inserting or removing the filtering member. The mouth piece D

will be connected with this extended end of the filtering member in any desired manner. The end 16 is furthermore provided with a passageway 31 extending axially

therethrough and has its forward end portion upturned, as at 33, and opening through an inclined or bevelled face 34 which is provided upon the top forward end of the cylinder portion 16. The ends 15 and 16 of the improved filter member C are connected by a relatively flat intermediate body portion 35, which preferably extends axially

of the aligning cylindrical shaped ends 15 and 16 so that the top surface 36 thereof

is relatively flat and is disposed below the groove 20 and the inlet opening 33. It is preferred that a projection 37, in the form of a partition be provided upwardly upon the surface 36 and being substantially semi-cylindrical in cross section for cooperation with the passageway 12 of the pipe stem 11. Apertures 38 and 39 may be provided in the intermediate portion 35 of the filter member C upon the forward and rear portions thereof. It is preferred that the end face 40 of the projection 37 which faces the bevelled surface 34 be likewise bevelled. The facing surfaces 41 and 42 of the end 15 15 and projection 37 are likewise bevelled in converging relation toward the intermediate portion 35.

In the mounting of the improved filter member C within the pipe stem 12, the end 20 15, of course, extends inwardly of the passageway 12 so that the same is disposed adjacent the bowl 10. The ends 15 and 16 snugly fit within the passageway 12 so that a draft passing through the pipe stem 25 11 will necessarily pass through the groove 20 and the passageway 31. When the improved filter arrangement C is thus disposed within the passageway 12, the passageway is subdivided into a forward upper chamber 30 45 and a rear upper chamber 46, which are respectively disposed intermediate the end 15 and projection 37, and the end 16 and projection 37. A relatively long lower chamber 35 47 is also provided, which communicates with the chambers 45 and 46 through the respective apertures 38 and 39.

The mouth piece D is provided with a stem portion 50, the outer surface of which is disposed flush with the peripheral surface of the outer end portion of the filter member, as can readily be seen in Figure 1 of the drawing. This mouth piece D of the improved pipe A is provided with a passageway 52 extending axially therewhrough and aligning with the passageway 31.

In operation, as the user draws upon the pipe, so to speak, the draft will be downwardly through the chamber 54 of the bowl 50 10 and through the groove 20 in the member C, entering the forward top chamber 45. The partition 37 completely fills the upper part of the passageway 12 intermediate the chambers 45 and 46, so that the draft 55 is baffled by this partition 37 and directed downwardly through the aperture 38 into the longitudinally extending lower chamber 47. The draft is baffled by both ends 15 and 16 within this chamber 47 so that the same pursues a path upwardly through the aperture 39 into the top rear chamber 46. At this point, the draft enters the offset 33 of the passageway 31, and from the passageway 31 enters the passageway 51 of 65 the mouth receiving member D and enters

the mouth of the user. By the provision of such structure, the draft is forced to pursue a tortuous path so that the nicotine from the smoke prior to entering the mouth of the smoker is filtered in chambers 45 and 46 70 and enters the relatively long chamber 47, as can readily be understood. The main baffle and filtering operation takes place in the foremost upper chamber 45, so that the nicotine in its condensed form settles into the 75 lower chamber 47. Due to the fact that the passageway 31 is offset as at 33, and communicates with the upper chamber 46, the nicotine will not enter the passageway 31 and consequently is prevented from entering the 80 mouth of the user, so that the smoke is refined and enters the mouth of the user in a desired condition.

From the foregoing description of this invention, it can readily be seen that a nicotine 85 filter arrangement for pipes has been provided in which the draft is not unduly obstructed as by absorbent masses and like expedients heretofore adopted. The construction of the pipe is practical and the diameters of the cylinder portions of the improved filter member C are relatively small, so that the improved arrangement is not cumbersome.

Various changes in the shape, size and 95 arrangement of parts may be made to the form of the invention shown, without departing from the spirit of the invention or the scope of the claims.

I claim:

1. As an article of manufacture, a filter 100 for tobacco pipes including cylindrical shaped ends connected by a relatively flat reduced intermediate portion, one of said ends having a groove extending longitudinally through the same to communicate above the top surface of said reduced intermediate portion, the other of said ends having a passageway extending axially and longitudinally therethrough provided with 105 an offset forward end opening upwardly above the top surface of said reduced flat intermediate portion, said intermediate flat portion having a projection of arcuate cross section extending upwardly of the top surface thereof intermediate the ends of said member and having an unbroken arcuate upper face, said intermediate portion apertured transversely therethrough upon opposite sides of said upwardly extending projection.

2. A pipe comprising a casing including 115 a bowl and a hollow stem portion extending from said bowl, a filter member removably fitting in said hollow stem and having a cylindrical inner forward end portion positioned adjacent the bowl and filling the 120 stem and a cylindrical rear end portion filling the outer end portion of the stem, a flat intermediate strip-like portion connecting 125 130

the cylindrical forward and rear end portions of the filter member and having its side edges engaging the walls of the stem and its upper and lower faces in spaced relation to the walls of the stem to provide spaces above and below the strip, the forward cylindrical end portion being provided with a smoke passage leading from said bowl to a point above the forward end of the intermediate strip and the rear end portion of the filter member having a longitudinally extending smoke passage extending substantially axially thereof for the major portion of its length and having its inner end portion directed upwardly and opening

through the inner end of the rear end portion above the upper face of the intermediate strip, and an enlargement extending upwardly from the intermediate strip intermediate the length thereof and forming a partition having close engagement with the walls of the stem to divide the space above the intermediate strip into separate end compartments, said intermediate strip being provided with openings between the partition and enlarged end portions to provide communication between the spaces above and below the intermediate strip. 20 25

OLLIE EARL NICHOLS.
